(57) **CLAIM**

The ornamental design for an electronic locker lock, as shown and described.

DESCRIPTION

FIG. 1 is a front, left perspective view of a first embodiment of an electronic locker lock, showing our new design;

FIG. 2 is a top plan view thereof;

FIG. 3 is a left side elevation view thereof;

FIG. 4 is a front elevation view thereof;

FIG. 5 is a right side elevation view thereof;

FIG. 6 is a bottom plan view thereof;

FIG. 7 is a front, left perspective view of a second embodiment of an electronic locker lock, showing our new design;

FIG. 8 is a top plan view thereof;

FIG. 9 is a left side elevation view thereof;

FIG. 10 is a front elevation view thereof;

FIG. 11 is a right side elevation view thereof;

FIG. 12 is a bottom plan view thereof;

FIG. 13 is a front, left perspective view of a third embodiment of an electronic locker lock, showing our new design;

FIG. 14 is a top plan view thereof;

FIG. 15 is a left side elevation view thereof;

FIG. 16 is a front elevation view thereof;

FIG. 17 is a right side elevation view thereof;

FIG. 18 is a bottom plan view thereof;

FIG. 19 is a front, left perspective view of a fourth embodiment of an electronic locker lock, showing our new design;

FIG. 20 is a top plan view thereof;

FIG. 21 is a left side elevation view thereof;

FIG. 22 is a front elevation view thereof;

FIG. 23 is a right side elevation view thereof; and,

FIG. 24 is a bottom plan view thereof.

Features shown in dashed lines are not part of the claimed design.

1 Claim, 4 Drawing Sheets
